WINDOW GUARD

Louis C. Stukenborg, Memphis, Tenn.

Application February 2, 1950, Serial No. 141,940

4 Claims. (Cl. 20—71)

1

This invention relates to improvements in window guards for preventing entrance to a building through a window, and has especial relation to guards which are readily installed individually in place, and as readily removed from within the building without the use of keys or tools to permit escape through the window in case of emergency, yet which cannot be removed from without the building.

Window guards are used to provide protection against access to buildings through the windows when open, but function to prevent exit from the building, which in emergencies, such as fires, may cause disaster. To minimize this, locks or other devices requiring the use of keys or tools have been provided as a part of the fastening means which release the guard and allow its removal, but absence of, or failure to locate the key or tool negates their effectiveness and value.

The primary object of the invention is to provide means for anchoring a window guard in place and its removal from within the building without the use of keys or tools, which means is readily operable at all times from within, but is inoperable from without the building.

The means by which the foregoing and other objects are accomplished and the manner of their accomplishment will readily be understood from the following specification on reference to the accompanying drawings, in which:

Fig. 1 is an elevational view showing the guard installed in a typical window, with one modification of a limit member furnishing part of my device installed.

Fig. 2 is a sectional elevation taken on the line II—II of Fig. 1, with the lower sash blocked against full raise and the guard locking means blocked against operation.

Fig. 3 is a similar sectional elevation on the same line of Fig. 1 with the limit means removed and the lower sash fully raised, releasing the guard locking means.

Fig. 4 is a sectional plan taken on the line IV—IV of Fig. 1, showing a threaded sleeve forming part of the locking means engaging complementary threads on the upper strut of the guard.

Fig. 5 is a similar sectional plan taken on the line V—V of Fig. 1 showing telescoping end of the lower strut of the guard.

Fig. 6 is an enlarged elevational view of the limit member, shown in Fig. 1, which blocks full raise of the lower sash.

Fig. 7 is a plan view taken on the line VII—VII of Fig. 6.

2

Fig. 8 is an elevational view, partly in section, showing an alternate form of limit member.

Fig. 9 is a similar elevational view partly in section, showing a further form of limit member or stop.

Referring now to the drawings in which the various parts are indicated by numerals:

Fig. 1 shows a typical window frame having side members 12, sill 14 and lintel 16, and the upper and lower sash 18 and 20. In accordance with the present invention, a guard 22 is mounted in the side grooves 12A, 12B of the frame in which the upper, and outer, sash 18 is mounted, the guard being in underlying relation to that sash and of height to prevent lowering of the sash.

The guard comprises horizontally disposed transverse upper and lower struts 24 and 25, convenient lengths of pipe which extend between the sides of the window frame and support a grill which may be vertically disposed bars 26 rigidly secured as by welding to the struts.

At one side of the window the struts 24 and 25 abut against an upright rail 28, to which they are preferably integrated as by welding, the rail being of width to lie in the groove 12A and preferably of height to extend from the window sill 14 to the under side of the fully raised upper sash 18. The opposite ends of the struts 24 and 25 terminate short of a similar rail 30 disposed in the groove 12B. The upper strut 24 is threaded to receive an internally threaded sleeve 32 which extends beyond the end of the strut into abutting engagement with the rail 30 and is held against vertical and lateral displacement by a stud 34, which stud is aligned with the strut and rigidly secured to and extends from the sleeve-abutting face of the rail. The sleeve 32 is provided with a rigidly attached, laterally extending handle 36, through which the sleeve may be turned to tighten it against the rail 30 and force the rails 28 and 30 oppositely into seating and guard retaining engagement in the grooves 12A and 12B of the window frame; or it may be reversely turned to loosen and release the rails from the grooves and permit removal of the guard.

The lower strut 25 is preferably unthreaded and slidably engages a sleeve 38 secured to and projecting from the rail 30 which prevents displacement of the lower strut 25 during tightening and loosening of the upper strut. The upper strut 24 is positioned in excess of the

55

length of the handle 36 below the bottoms of the bottom rails 40 and 42 of the upper and lower sashes 18 and 20 respectively, when both are fully raised as shown in Fig. 3, so that the handle may be freely turned to screw the sleeve 32 along the strut 24 to effect securing or removal of the guard.

To prevent removal of the guard a removable stop is placed above the top of the lower sash which prevents raising of the bottom rail 42 of that sash beyond the swing of the handle 36. Where the lower sash is balanced by a counter-weight, not shown, through sash cords 44 which pass over pulleys 46 mounted in the window frame, raising is preferably limited by placing around at least one of the cords 44 a stop block 48 having a hole 48A embracing the cord. The block rests on the top of the lower sash and moves upward therewith until it engages the pulley 46 and stops the sash movement with the lower rail 42 of the sash below the lower rail 40 of the upper sash, and in the path of movement of the handle, preventing that handle movement which is necessary to turn the sleeve 32 and effect release and removal of the guard.

The block 48 is conveniently made of hard vulcanized rubber, such as is used in automobile tire casings, and is vertically slotted at 48B to permit its placing around or removal from the cord.

Where windows are not equipped with sash cords a different type of stop must be employed, which type may be used with windows whether having sash cords or not.

Such a stop is shown in Fig. 3 and comprises a stop pin, or member, 50 which is removably interposed between the top of the sash and the lintel 16, the stop 50 being carried by a socket 52 secured on the top of the sash as by screws 54. The socket 52 obviously prevents full raising of the sash even when the pin is removed, and must be taken into account in the positioning of the upper strut 24 of the guard and the length of the handle 36, which latter must clear the bottom rail 42 even though its raise be limited by the socket 52.

In Fig. 9, a further form of stop is shown which comprises a block 56 as of wood, preferably of size to snugly fit in either of the grooves 12A or 12B in which the sash 20 is mounted, and is of length to limit the raise of the sash as does the stop 48 or the stop 50. The block may have upwardly and downwardly projecting points 58 which engage the underside of the window lintel 16 and the top of the sash respectively, but in any case is easily removable in case of emergency.

In some cases it is found that the window frame is not provided with an outer stile for retaining the upper sash 18, and no actual grooves 12A, 12B exist in which the upper sash is mounted. If desired the rails 28 and 30 of the guards may be provided with sharpened, outwardly projecting points 60, Fig. 1, preferably disposed above and below the upper threaded strut 24, which points are embedded in the sides of the window frame by tightening of the threaded sleeve 32 during installation of the guard.

It will be noted that the guard underlies the upper sash and prevents lowering of that sash to obtain access to, and removal of, the stops of either type.

It will be understood that the design and type

of stop is illustrative only and may be varied from, and that changes may be made in the combination and arrangement of the several parts provided such changes fall within the scope of the claims hereto appended.

I claim:

1. A window guard of the type which includes a pair of side rails and upper and lower adjustable length transverse struts, respectively spaced 10 below the upper, and above the lower ends of the guard; said guard having an overall height substantially equalling the height of the window space to be guarded, and a said upper strut including a first portion rigidly secured at one end 15 to a first of said rails and having its opposite end screw threaded and terminating in spaced relation to the second of said rails, and a second portion threadedly engaging the threaded end of said first portion and extending axially therefrom into 20 abutting relation with said second rail, a projecting member rigidly secured to said second rail, turnably centering the abutting end of said second strut portion, and an arm rigidly secured to said second portion and extending laterally therefrom, said arm being of length to extend into 25 proximity to the top of said guard but not therebeyond.

2. A window guard in accordance with claim 1 in which said side rails extend above and below 30 all other parts of said guard and determine the overall height of the guard.

3. A window guard of the type which includes a pair of side rails and upper and lower adjustable length transverse struts, respectively spaced 35 below the upper, and above the lower ends of the guard; said guard having an overall height substantially equalling the height of the window space to be guarded, and a said upper strut including a first portion rigidly secured at one end 40 to a first of said rails and having its opposite end externally screw threaded and terminating in spaced relation to the second of said rails, and an internally threaded sleeve portion engaging the threaded end of said first portion and extending 45 axially therefrom into abutting relation with said second rail, a stub rigidly secured to said second rail, turnably engaging and centering the abutting end of said sleeve portion, and an arm rigidly secured to said sleeve portion and extending laterally therefrom, said arm being of length to extend into proximity to the top of said guard but not therebeyond.

4. A window guard in accordance with claim 3 in which said arm is secured to said sleeve in adjacency to the rail abutting end of said sleeve.

LOUIS C. STUKENBORG.
